UNITED STATES PATENT OFFICE.

WILKIE H. HOLTBY, OF MANGUM, OKLAHOMA.

TRAMPER.

Application filed September 5, 1919. Serial No. 321,750.

To all whom it may concern:

Be it known that I, WILKIE H. HOLTBY, a citizen of the United States, residing at Mangum, in the county of Greer and State 5 of Oklahoma, have invented new and useful Improvements in Trampers, of which the following is a specification.

My invention relates to improvements in trampers for packing or baling cotton or the 10 like.

An important object of the invention is to provide mechanical means for feeding the cotton or the like into the press box, such means operating in conjunction with the 15 trumper head, so that such feeding means automatically stops upon the descent of the trumper head.

A further object of the invention is to provide means whereby the rake, employed to 20 discharge the cotton into the central portion of the press box, is automatically moved out of the path of travel of the trumper head, by means actuated by such trumper head.

A further object of the invention is to provide automatic means to actuate the valve 25 shifting mechanism of the trumper cylinder, should the cylinder fail to move downwardly sufficiently whereby means travelling with it are rendered incapable of actuating 30 the valve shifting mechanism.

Other objects and advantages of the invention will be apparent during the course 35 of the following description.

In the accompanying drawings forming a part of this specification, and in which like 40 numerals are employed to designate like parts throughout the same,

Figure 1 is a side elevation of apparatus embodying my invention,

Figure 2 is an end elevation of the same, parts being shown in section,

Figure 3 is a detail section taken on line 3—3 of Figure 1,

Figure 4 is a front side elevation of a bar 45 or rail,

Figure 5 is an edge elevation of the same,

Figure 6 is a rear side elevation of the same,

Figure 7 is a plan view of the valve shifting mechanism and associated elements,

Figure 8 is an elevation of the front side of the same,

Figure 9 is an elevation of the rear side,

Figure 10 is a transverse section taken on 55 line 10—10 of Figure 7,

Figure 11 is a side elevation of the rake or feeding device,

Figure 12 is a partly diagrammatic view of a valve and associated elements,

In the drawings, wherein for the purpose 60 of illustration is shown a preferred embodiment of my invention, the numeral 15 designates a horizontally rotatable supporting frame, secured to a vertical post 16, adapted to turn on its longitudinal axis. The frame 65 15 carries a pair of press boxes 17, of any well known or preferred construction. The press boxes 17 are provided at their upper ends with a frame or flange 18, and each frame has a recess 19, adapted for the 70 reception of a vertical lock rod 20 which serves to normally prevent rotation of the frame 15.

Arranged above the press boxes 17 is a 75 lower horizontal frame or support 21, having connection with an upper horizontal support 22, as shown. Arranged above each press box 17, when it is shifted to the active position, to the left, are ends 23, which are suitably supported. These ends are 80 included in a feed chute for the press box, the opposite sides of which will now be described. The rear side of this feed chute is open and receives the lower end of an inclined trough 24, within which the cotton 85 or the like is fed. This trough receives therein a feeding device in the form of a rake 25 (see Figure 11) embodying tines 26, carried by a transverse bar 27. The transverse bar 27 has trunnions 28 and 29 90 secured to its opposite ends, which are pivoted within beams 30 and 31. A second transverse bar 32 is provided at its ends with trunnions 33 and 34, pivoted in the beams 30 and 31. A central beam or tongue 95 35 is rigidly secured to the beam 32, and is also connected with diagonal braces 36, secured to the beam 32. The beam 31 is provided at its free end with a weight 37, to 100 compensate for the weight of the rake.

At its upper end the beam 35 is provided with a bearing 38, pivotally receiving a pin secured to one end of a crank arm 39, having a counter weight 40 secured to its opposite end. This crank arm is rigidly secured to 105 a shaft 42, journaled through bearings 43, and driven by a sprocket wheel 44, engaging a downwardly extending sprocket chain 45, which in turn engages a sprocket wheel 46.

The trunnion 29 is provided with a crank 110

47, to which is rigidly secured a suitably stiff spring 48, carrying a roller 49, at its free end, which travels in contact with a cam track 50, held stationary on the trough 5 24. An upper spring 51, has its free end engaged with and projecting beyond the roller 49. This upper spring is rigidly secured to a crank 53, carried by the trunnion 34. The function of the upper spring is to 10 cause the rake to move outwardly and laterally, so that its tines will be withdrawn from the path of travel of the trumper head, should the rake stop with its tines in such path of travel. The lower spring imparts 15 to the rake a lateral swinging movement, as it is raised and lowered, by coacting with the cam track 50.

The opposite side of the feed chute is closed by a tripping rack or device 54, embodying spaced slats 55, rigidly secured at their upper ends to a horizontal strip 56. This strip is hinged, as shown at 57 with the forward side of the upper frame 22, to swing outwardly. A crank-arm 58 is rigidly secured to the strip 56, and has adjustable pivotal connection as at 58^a (see Fig. 3) with a link 59, the upper end of which operates through a stationary apertured guide bracket 60. The link 59 normally engages 30 beneath a cam crank 61, rigidly secured to one end of a horizontal rock shaft 62, journaled in suitable bearings. The opposite end of the rock shaft 62 carries a trip 63, for a purpose to be described.

35 A second horizontal rock shaft 64 is arranged near and beneath the rock shaft 62 and carries a crank 65, which is pivoted to the lock rod 20. A second crank 66 is rigidly secured to this rock shaft 64, and engages beneath the link 59. It is thus seen that when the lock rod 20 is elevated to release the swinging frame 15, the crank 66 will move upwardly and the link 59 will be shifted upwardly to disengage the cam crank 40 61, so that the longitudinal movement of the link 59 cannot move the cam crank 61.

The sprocket wheel 46 is loose upon a shaft 67, journaled through bearings 68. This sprocket wheel embodies a hub 69, having a clutch element 70, to engage a coacting clutch element 71, which is rigidly secured to the shaft 67. The hub 69 has an annular groove 72, receiving the forked end of an arm 73, which is bolted as shown at 74, to a main shifting bar 75. In Figure 7 the main shifting bar 75 is shown operated through openings in standards 77. This main shifting bar 75 is shown moved to the right, as viewed in Figures 7 and 8 when it is shifted 45 to the left, the sprocket wheel 46 will be shifted to the left, and rendered idle. This stops the operation of the rake or feeding device.

The trip 63 which is located near and 50 above a latch 78', is pivoted at 79. This latch

has its forward hooked end 80 engaging a stud 81 carried by a valve shifting bar 75'. When a sufficient amount of cotton has been fed into the chute, it acts upon the pressure device 54, swinging it outwardly upon its pivot. This outward movement of the device 54 turns the rock shaft 62, through the medium of link 59 and element 61, in a direction to cause the trip 63 to depress the tail of the latch 78', and release the bar 75', which is shifted to the left as viewed in Figures 7 and 8. When this occurs, the trumper head 52 begins to descend, as the valve 122 to be hereinafter more fully described actuated by the valve shifting bar 75' is opened to supply pressure to the upper end of the cylinder, to be described.

As the trumper head 52 descends, a vertical rail 82, secured to this trumper head, and operated in stationary guides 83, moves downwardly. Tracks 84 and 85 secured upon one side of the rail 82 form a cam groove 86, receiving a roller 87, pivoted to the left end of the main shifting bar 75 by a stud 88. The bar 75 is thereby drawn to the left and the arm 73 will shift the sprocket wheel 46 to the left as viewed in Figures 7 and 8 and render it idle. It is thus seen that the feeding device or rake is stopped upon the starting of the downward movement of the trumper head. The stud 88 has a catch 89 pivoted thereto, having a head 90, to engage a stud 91, carried by the bar 75'. When the bar 75' is shifted to the left, as stated, it is locked in this position by the head 90 engaging the stud 91, and the movement of the bar 75 to the left, which is comparatively slow, effects a further movement to the left of the bar 75', thereby further opening the valve 122 to be hereinafter more fully described to supply 95 an increased volume of steam to the top of the cylinder.

The bar 75' has connection with a leaf spring 92, which is shown as flexed to the right in Figure 8, from its neutral vertical position, and hence it is placed under tension so that it will automatically shift the bar 75' to the left, as above stated. The spring 92 is clamped at its upper end to a transverse rock bar 93, having trunnions 94, pivoted in stationary standards 95. A second leaf spring 96 is clamped to the rock bar 93, and extends downwardly for engagement with a vertical bar 97 (see Figure 9) which 100 is rigidly secured to a spring tension bar 98, as shown at 99. The bar 98 is reciprocatory and carries a roller 100, pivoted thereto, and adapted to operate within an inclined groove 101, formed by tracks 102 and 103, rigidly 105 secured to the opposite side of the vertically movable rail 82.

When the bar 75' as viewed in Figures 7 and 8 is shifted to the left, the spring 92 is returned to the neutral position, and when 110

the plunger or trumper head 52 nears the end of its down stroke, the rail 82 will descend sufficiently so that the roller 100 will pass within the upper portion of the groove 101, drawing the spring tension bar 98 to the right, which will turn the rock bar 93, and place spring 92 under tension, to shift bar 75' to the right, when released by the catch 89. The catch 89 will release the bar 10 when the rail 82 moves downwardly sufficiently so that the trip 104 rigidly secured to the rail 82 contacts with the tail of the catch 89 and swings its head 90 upwardly.

At its right end, the bar 75' carries a lateral extension 105, adapted to contact with the right end of bar 75, and also with a stop 106, which is adjustable.

The pivot 79 of the catch 78' is preferably carried by a horizontally adjustable support 20 or base 107, as clearly shown in Figure 8.

When the tension bar 98 is shifted to the right, its cam face 108 (Figures 7 and 9) engages a resilient rod 109, rigidly secured to a slide rod 110, operating in guides 111. The resilient rod is curved and has a thread 112, engaging a worm 113, on the shaft 67. At its left end, the slide rod 110 has a lateral extension 114, to engage an arm 115, carried by the catch 89. It is thus seen that upon the descent of the trumper head, the rod 109 will have its thread 112 thrown into engagement with the threads or worm 113, and the slide rod 110 will be moved slowly to the left. In case the bale is large and the trumper head cannot move downwardly sufficiently so that the trip will engage the catch 89, to reverse the operation of the valve, the rod 110 will then move over sufficiently so that its extension 114 engages the arm 115 and 40 operates the catch 89. The rod 109 is tensioned to move away from the worm 113, and when the spring tension bar 98 is shifted to the left, the thread 112 will disengage the worm, the rod 110 being returned to the 45 right by a spring 115'.

The trumper head 52 is connected with a piston rod 116, connected with a piston 117, operating in a cylinder 118. A pipe 119 leads into one end of the cylinder 118 and a pipe 50 120 leads into the opposite end of this cylinder. The pipes 119 and 120 are connected with a valve casing 121, at diametrically opposite points. This valve casing is included in a four-way valve structure, and contains 55 a valve 122, having oppositely arranged ports 123 and 124. The valve casing 121 is provided with an exhaust pipe 125 and an inlet pipe 126, diametrically opposite each other. The inlet pipe leads to a source of steam or 60 fluid pressure 127. It is thus seen that the four-way valve and associated elements is adapted to alternately supply steam to one end of the cylinder while it is exhausting the steam from the opposite end.

The valve 123 may be turned by a crank 65 128, connected with a link 129, secured to an arm or bracket, carried by the valve shifting bar 75'. When the bar 75' is released, at the begining of the operation of the trumper head, the piston 117 is in the 70 elevated position, and this bar will be shifted to the right to turn the valve 123 to the position shown in Figure 12, so that the steam will act upon the upper side of the piston, and move it downwardly. When the bar 75' 75 becomes locked to the main shifting bar 75, by means of the latch 89, and the bar 75 is drawn further to the left, the bar 75' is shifted further to the left and valve 123 turned to a further extent, for increasing 80 the volume of steam supplied to the top of the cylinder, as the trumper head approaches the end of its downward travel.

In the operation of the apparatus, the trumper head 52 may be assumed to be in 85 the elevated position, and the shaft 67 being continuously rotated. The cotton or the like is fed into the inclined trough 24 and is engaged by the rake, which is adapted to move upwardly above the cotton in the 90 trough and then descend, while partaking of a lateral movement, to feed the cotton into the central portion of the press box and chute. When the press box becomes 95 filled and the cotton accumulates in the chute, the tripping device 54 is operated, to release the bar 75' by the action of trip 63 which effects disengagement of the latch 78' from the valve shifting bar 75'. When thus released the spring 92 which is then 100 under tension is effective to move the valve shifting bar to the left (as viewed in Figures 7 and 8). This movement of the valve shifting bar moves the valve 122 so as to admit pressure into the top of the cylinder 118 105 and thus cause the trumper to move downwardly. This movement of the valve shifting bar 75' also connects it with the main shifting bar 75, the catch 89 effecting this connection. The initial downward movement of the trumper results in a movement of the main shifting bar to the left as viewed 110 in Figures 7 and 8, by reason of the action of the cam groove 86 and the roller 87, and as the valve shifting bar is at this time connected with the main shifting bar, it is constrained to move to the left with the main shifting bar whereby the valve 122 is further opened to admit a greater volume of steam into the top of the cylinder 118. The 115 movement of the main shifting bar 75 serves to move the sprocket wheel 46 so as to disengage its clutch element 70 from the clutch element 71 and thus stop the operation of the rake.

As the trumper continues to descend, the spring tension bar 98 is moved to the right (as viewed in Figures 7 and 8) by means of

the action of the roller 100 and the cam groove 101 and this tensions the spring 92 so that it will be effective to move the bar 75' to the right when this bar is released 5 from its connection with the main shifting bar 75. When the trumper head moves downwardly sufficiently the trip 104 strikes the catch 89 and releases the bar 75' from its connection with the bar 75 and thus permits the spring 92 to move the bar 75' to the right (as viewed in Figures 7 and 8). Should the press box contain so much material that the trumper head cannot move downwardly to such an extent as to permit 10 engagement of the trip 104 with the catch 89, the disengagement of the trip is effected by means of the extension 114 of the slide rod which extension engages the arm 115 of the catch, the slide rod being moved to effect 15 this action by means of its thread 112 and the screw 113, the thread and screw being engaged by the action of the cam 108 of the spring tension bar 98 when the spring tension bar is moved to the right (as viewed 20 in Figures 7 and 8). In either event the catch 89 is moved to release the valve shifting bar 75' and it is shifted to the right by the action of the spring 92, and this movement of the valve shifting bar 75' reverses 25 the position of the valve 122 and admits steam into the lower end of the cylinder 118 to move the trumper head upwardly. It is obvious that when the steam is being admitted to the lower end of the cylinder 30 it is being exhausted by the upper end of the cylinder through the pipes 119 and 125; and that when the steam is being admitted into the upper end of the cylinder 118, the steam is being exhausted from the 35 lower end of the cylinder by means of pipes 120 and 125. When the valve shifting bar 75' thus moves to the right as viewed in Figures 7 and 8 under the action of the spring 92, it is engaged by the latch 78' and 40 maintained in this position even after the trumper head has ascended and the spring tension bar 98 has been moved in the opposite direction by means of the roller 100 and cam groove 101 to place the spring 92 under 45 an opposite tension that is under a tension tending to move the valve shifting bar 75' to the left (as viewed in Figures 7 and 8). The upward movement of the trumper also 50 repositions the main shifting bar so as to again engage the clutch element 70 and 71 and renew the operation of the feeding device.

It is to be understood that the form of 55 my invention herewith shown and described 60 is to be taken as a preferred example of the same, and that various changes in the shape, size, and arrangement of parts may be resorted to without departing from the spirit

of my invention, or the scope of the subjoined claims.

Having thus described my invention, I claim:

1. In an apparatus of the character described, a press box, an inclined trough arranged near the upper end of the press box, a rake operating within the trough, means for actuating said rake including a continuously rotating shaft, motion transmission means between said shaft and said rake including clutch mechanism and controlling mechanism for said clutch including a shiftable bar operated by the movement of the trumper head and connecting means between said bar and said clutch mechanism.

2. In an apparatus of the character described, a press box, a trumper head for coaction with the press box, a cylinder, a piston operating in the cylinder and connected with the trumper head, a valve to control the inlet of fluid pressure to the cylinder, and valve shifting mechanism for the valves including a valve shifting bar connected with the valve, a main shifting bar carrying a roller, means for releasably locking the bars together, a spring tension bar carrying a roller, a rail connected with the trumper head for movement therewith and having cam grooves for the reception of said rollers, and means for releasing the bars from each other.

3. In an apparatus of the character described, a press box, a trumper head for coaction with the press box, a cylinder, a piston operating in the cylinder and connected with the trumper head, a valve to control the inlet of fluid pressure to the cylinder, and valve shifting mechanism for the valves including a valve shifting bar connected with the valve, a main shifting bar carrying a roller, means for releasably locking the bars together, a spring tension bar carrying a roller, a rail connected with the trumper head for movement therewith and having cam grooves for the reception of said rollers, a trip carried by the trumper for releasing said bars from each other, and auxiliary means operating independently of the trumper for securing release of said bars from each other.

4. In apparatus of the character described, a press box, a laterally movable tripping element arranged near the press box to be moved by material fed into the press box, a trumper head for coaction with the press box, means to move the trumper head, a reciprocating element to move in one direction when released for actuating said means, a latch to normally hold the reciprocating element against movement, means operated by the laterally movable tripping element to actuate the latch, a de-

vice to feed material into the press box, driving means for the device, and means to render the driving means idle upon the downward movement of the trumper head.

5. In apparatus of the character described, a press box, a laterally movable tripping element arranged near the press box to be moved by material fed into the press box, a trumper head for coaction with the press box, a cylinder, a plunger operating within the cylinder and connected with the trumper head, a valve to control the inlet of fluid pressure to the opposite ends of the cylinder, a valve shifting bar connected with the valve, a spring to move the valve shifting bar in one direction, a latch to hold the bar against such movement, means operated by the laterally movable tripping element to actuate the latch, feeding mechanism to supply material to the press box, driving means for the feeding mechanism, a main shifting bar having means to render the driving means inactive, and means connected with the trumper head to move the main shifting bar.

6. In apparatus of the character described, a press box, a laterally movable tripping element arranged near the press box, a trumper head arranged near the press box, a cylinder, a plunger operating within the cylinder and connected with the trumper head, a valve to control the inlet of fluid pressure to the opposite ends of the cylinder, a valve shifting bar connected with the valve, a spring to move the valve shifting bar in one direction, a latch to hold the bar against such movement, and means operated by the laterally movable tripping element to actuate the latch.

7. In apparatus of the character described, a pressure box, a trumper head for coaction with the pressure box, a cylinder, a plunger operating within the cylinder and connected with the trumper head, a valve to control the inlet of fluid pressure to the cylinder, a valve shifting bar connected with the valve, yielding means to move the bar in either direction, a catch to hold the bar against movement in one direction, means operated by the pressure from the material fed into the press box to actuate the catch, a main shifting bar, a catch carried by the main shifting bar and adapted to engage with the valve shifting bar for connecting these two bars, a member connected with the trumper head to shift the main shifting bar, a feeding device for the press box, driving means for the feeding device, and an element to render the driving means inactive secured to the main shifting bar to be actuated thereby.

8. In apparatus of the character described, a pressure box, a trumper head for coaction with the pressure box, a cylinder, a plunger operating within the cylinder and connected

with the trumper head, a valve to control the inlet of fluid pressure to the cylinder, a valve shifting bar connected with the valve, yielding means connected with the bar, a catch arranged near one end of the bar to hold it against movement in one direction, means to operate the catch, a main shifting bar carrying a roller, a catch secured to the main shifting bar near the opposite end of the valve shifting bar and serving to lock these two bars together, feeding means for the press box, driving means for the feeding means having its operation controlled by the main shifting bar, a spring tension bar carrying a roller, a device shifted by the spring tension bar and having connection with said spring, and a rail connected with the trumper head for movement therewith and having cam grooves for the reception of said rollers.

9. In apparatus of the character described, a press box, a trumper head to coact therewith, a rotatable shaft having screw-threads, a gear carried by the shaft, feeding means for the press box, driving means between the feeding means and gear, a main shifting bar having a roller and provided with means to render the gear idle upon its shaft when moved in one direction, a second bar having a roller and provided with a cam face, a member having a thread to engage with the screw-threads and actuated by the cam face, a rail connected with the trumper head and having cam grooves to receive the rollers, means to move the trumper head downwardly, and means actuated by said member to stop such downward movement.

10. In apparatus of the character described, the combination with a movable frame, of a plurality of press boxes carried therein, a trumper head to coact with each press box when shifted to the active position, a lock bar to normally hold the press box in the active position, a tripping device to be moved by material fed into the press box, a link moved by the tripping device, a cam crank normally engaged by the link, means actuated by the cam crank to move the trumper head downwardly, and means moved by the movement of the lock bar in one direction to cause the link to disengage the cam crank.

11. In apparatus of the character described, a press box, an inclined trough arranged near the upper end of the press box, a rake operating within the trough and embodying a frame, a forward transverse bar pivoted to the frame and carrying tines, a crank secured to one end of the forward transverse bar, a spring secured to the crank, a roller carried by the spring, a cam track on the trough to engage the roller, a second spring secured to the frame above the first named spring and projecting over the press box and adapted to

- effect a lateral movement of the rake, means to effect a longitudinal movement of the rake, a tramper head to coact with the press box and adapted to engage the second named 5 spring, and means to move the tramper head.
12. In apparatus of the character described, a press box, an inclined trough arranged near the upper end of the press box, 10 a rake operating within the trough, embodying a frame, a forward-transverse bar pivoted to the frame and carrying tines, a crank secured to one end of the forward transverse bar, a spring secured to the crank, a roller 15 carried by the spring, and a cam track arranged on the trough and engaged by the roller.
13. In apparatus of the character described, a pressure box, a tramper head for 20 coaction with the pressure box, a cylinder, a plunger operating within the cylinder and connected with the tramper head, a valve to control the inlet of fluid pressure to the cylinder, a valve shifting bar connected with 25 the valve, yielding means to move the bar in either direction, a catch to hold the bar against movement in one direction, means operated by the pressure from the material fed into the press box to actuate the catch, 30 a main shifting bar, a catch carried by the main shifting bar and adapted to engage with the valve shifting bar for connecting these two bars, and a member connected with 35 the tramper head to shift the main shifting bar.
14. In apparatus of the character described, a pressure box, a tramper head for coaction with the pressure box, a cylinder, a plunger operating within the cylinder and connected with the tramper head, a valve to control the inlet of fluid pressure to the cylinder, a valve shifting bar connected with the valve, yielding means connected with the bar, a catch arranged near one end of the 40 bar to hold it against movement in one direction, means to operate the catch, a main shifting bar carrying a roller, a catch secured to the main shifting bar near the opposite end of the valve shifting bar and serving to lock these two bars together, a spring tension bar carrying a roller, a device shifted by the spring tension bar and having connection with said spring, and a rail connected with the tramper head for movement therewith and having cam grooves for the 45 reception of said rollers.
15. In an apparatus of the character described, a press box, a tramper head for coaction with the press box, a cylinder, a plunger operating within the cylinder and connected with the tramper head, a valve to control the inlet of fluid pressure to the cylinder, 50 a valve shifting mechanism for the valve including a valve shifting bar connected with the valve, spring actuated means connected with the bar, a main shifting bar carrying a roller, means for releasably locking the bars together, a spring tension bar carrying a roller and a rail connected with the tramper head for movement therewith and having cam grooves for the reception of said rollers.
16. In an apparatus of the character described, a press box, a tramper head for coaction with the press box, a cylinder, a plunger operating within the cylinder and connected with the tramper head, a valve to control the inlet of fluid pressure to the cylinder, a valve shifting mechanism for the valve including shifting bars carrying rollers and a rail connected with the tramper head for movement therewith and having cam grooves for the reception of said rollers.
17. In an apparatus of the character described, a press box, a tramper head for coaction with the press box, a cylinder, a plunger operating within the cylinder and connected with the tramper head, a valve to control the inlet of fluid pressure to the cylinder, a valve shifting mechanism for the valve including shifting bars carrying rollers, spring means for actuating one of said bars, and a rail connected with the tramper head for movement therewith and having cam grooves for the reception of said rollers.
18. In an apparatus of the character described, a press box, a tramper head for coaction with the press box, a cylinder, a plunger operating within the cylinder and connected with the tramper head, a valve to control the inlet of fluid pressure to the cylinder, a valve shifting mechanism for the valve including shifting bars, spring means for actuating one of said bars, and means actuated by the movement of the tramper head for shifting said bars.
19. In an apparatus of the character described, a press box, a tramper for coacting with said press box, a piston operating in the cylinder and connected with the tramper head, a valve to control the inlet of fluid to the cylinder, a valve shifting mechanism for the valve including a shifting bar, spring means for actuating said bar, means actuated by the movement of the tramper head for tensioning said spring means, feeding mechanism for the press box, drive mechanism for the feeding mechanism and controlling mechanism for the drive mechanism including a clutch, and a tripping device associated with the press box controlling said clutch.

WILKIE H. HOLTBY.
